UNITED STATES PATENT OFFICE.

JAMES POWELL FISHER, OF BARTLESVILLE, OKLAHOMA, ASSIGNOR, BY MESNE ASSIGNMENTS, TO DOHERTY RESEARCH COMPANY, OF NEW YORK, N. Y., A CORPORATION OF DELAWARE.

FLUID-CONTROLLING MECHANISM.

Application filed November 15, 1920. Serial No. 424,144.

This invention relates to fluid controlling mechanism and more particularly to mechanism adapted for use in a gas distributing system to limit the quantity of gas which 5 may flow through the individual service lines and to regulate the pressure of the gas in the service lines.

In the distribution of natural and artificial gas as heretofore practiced, the amount 10 of gas which any consumer might withdraw from the mains has been limited only by the pressure of the gas in the mains and the capacity of the line or lines of piping by which the consumer is served. Consequently, 15 either through accident to a service line or because of abnormal demand on the part of the consumer, gas might be taken from the supply mains along the line in quantities many times greater than the normal demand on the line. Manifestly, such an excessive demand might occur simultaneously 20 on a number of service lines. Under such conditions, in order, so far as possible, to insure an adequate supply of gas to all consumers at all times, it has been necessary to 25 maintain relatively high pressures in the supply mains, entailing greater leakage and loss of gas than would occur at lower pressures. Moreover, damage and annoyance 30 have often been caused to consumers, more especially to those who derive their supply of gas from portions of the mains relatively remote from the source of supply to the mains, through inability to obtain a normal 35 supply of gas by reason of excessive demands on the part of other consumers.

Gas distributing systems are commonly 40 divided into districts, each having a regulator for determining the pressure at which gas is supplied to the district mains. The district mains are preferably large enough 45 so that an adequate supply of gas may be delivered to each consumer with relatively low pressure in the mains. When, however, the district mains are small in proportion to the demand on them, it is necessary to maintain the gas at the district regulator under high pressure with large differential at times of extreme use of gas between the pressure of 50 the gas at the regulator and that on service

lines remote from the regulator. In such cases, the pressures of the gas in portions of the district mains is too great to permit it to be satisfactorily burned for most purposes including household use.

It is an object of the invention to provide mechanism which will limit the demand on the service lines of a gas distributing system, and which will regulate the pressure of the gas in the service lines to the end that each consumer served by the system may be assured at all times of a normal supply of gas at a pressure best suited to his requirements.

With the above-mentioned object in view, 65 an important feature of the invention comprises a housing constructed to allow fluid such, for example, as natural or artificial gas, to pass through it and containing means controlled by the fluid for limiting the rate 70 of flow of fluid through the housing and regulating the pressure at which the fluid is delivered from the housing.

In accordance with a further feature of the invention, means is provided for causing 75 a drop in pressure of fluid as it passes through a housing or other fluid conductor, together with means for utilizing the pressure differential on opposite sides of the first-mentioned means to control the rate of flow 80 of fluid through the conductor and means for regulating the pressure at which the fluid issues from the conductor. In the illustrated construction, the flow of the fluid is controlled by a valve, and mechanism 85 is provided for operating the valve both in accordance with the pressure differential of the fluid at certain points in the conductor, and in accordance with the pressure of the fluid on the delivery side of the conductor.

Another feature of the invention pertains to the provision in a fluid conductor of a valve for controlling the flow of fluid through the conductor and a pair of diaphragms operable to control the valve selectively and independently in accordance with varying conditions of flow of fluid through the conductor. As shown, the diaphragms are joined to the valve by lost mo- 100

tion connections constructed and arranged to cause the valve to be raised toward closed position upon elevation of either of the diaphragms without affecting the position of the other diaphragm.

A still further feature of the invention resides in a fluid-conducting housing containing a controlling valve, a diaphragm to which the valve is operatively connected, and an orifice disk for inducing drop in pressure of fluid passing through the housing, the housing being constructed to cause pressure differential on opposite sides of the disk to be transmitted to opposite sides of the diaphragm so that the valve is made to control the flow of fluid through the device in accordance with the pressure differential produced by the orifice disk.

Other objects and features of the invention will appear as the description proceeds and will be pointed out in the appended claims.

In the drawings,

Fig. 1 is a view in plan of a fluid controlling device embodying the preferred form of the invention;

Fig. 10 is a view in sectional elevation of the fluid controlling device in a form in which it may be employed to control the rate of flow of gas without pressure regulation.

The illustrated device comprises a housing 2 constructed to serve as a conductor for gas or other fluid and provided with inlet and outlet openings 4 and 6 respectively. As shown, the frame structure of the housing 2 is shaped inwardly of the inlet opening 4 to form an inlet chamber 8 communicating with a channel 10. The channel 10 is separated by an upper wall 12 from the lower portion of a diaphragm chamber 14 and by a lower wall 16 from passages 18 and 20 (Figs. 1 and 3) extending downwardly from the diaphragm chamber 14 and meeting below the wall 16.

The walls 12 and 16 are provided with openings in which is seated a valve cage 22 (Figs. 8 and 9) comprising upper and lower rings 24 and 26 respectively joined integrally by bars 28 spaced apart to afford passages 30 between them. The passages 30 allow gas to flow from the channel 10 to the interior of the valve cage, and ports 32 and 34 located centrally of the rings 24 and 26 respectively permit it to pass upwardly and downwardly from the valve cage, thus establishing fluid communication between the inlet chamber 8 and the diaphragm chamber 14 both directly and through the passages 18 and 20. Preferably, and in the illustrated construction, the upper ring 24 of the valve cage 22 is provided at its top with an outwardly projecting flange or rim 36 constructed to fit into a circular channel 38 on the upper side of the wall 12 and is formed below the flange 36 with external screw threads adapted for meshing engagement with threads about the opening in the wall 12. The lower ring 26 is shouldered at 40 to match a correspondingly shaped groove 42 in the wall 16. This construction enables the valve cage to be firmly secured in place in the housing 2 but renders it capable of ready removal from the housing, when desired. In order to facilitate the removal of the valve cage from the housing, the upper ring 24 may be formed with inwardly extending ears 44 provided with sockets 46 adapted to receive appropriately shaped elements on a spanner wrench or the like.

The housing 2 is formed to provide an outlet conduit comprising a chamber 46 communicating with the outlet opening 6 and demarcated from the channel 10 and passages 18 and 20 by a wall 48 and from the diaphragm chamber 14 by a wall 50. An opening 52 in the wall 50 allows gas to pass from the diaphragm chamber to the outlet chamber 46. From the foregoing, it will be understood that the course followed by gas in passing through the housing 2 is from the inlet opening 4 through the inlet chamber 8 and channel 10 to the interior of the valve cage 22; thence upwardly through the port 32 directly to the diaphragm chamber 14, or downwardly through the port 34 and upwardly through the passages 18 and 20 to the diaphragm chamber; and then through the opening 52 in the wall 50 to the outlet chamber 46 and outlet opening 6.

As hereinbefore indicated, means is provided both for limiting the rate of flow of fluid through the housing 2 and regulating the pressure at which fluid is delivered from the housing. Preferably, and as shown, such means includes a balanced poppet valve 54 (Fig. 4) comprising a sleeved portion 56 pinned to a stem 58 and formed with horizontally disposed circular flanges 60 and 62 operable upon upward movement of

the valve 54 to close the ports 32 and 34 respectively. The contacting surfaces of the rings 24 and 26 and the flanges 60 and 62 of the valve 54 are bevelled to insure smooth action of the valve. Vertically disposed wings 64 projecting outwardly from the sleeved portion 56 of the valve intermediate between the flanges 60 and 62 and above the flange 60 guide the valve in its up and down movements and tend to effect uniform flow of gas throughout the area of the ports 32 and 34. The housing 2 is preferably provided below the valve 54 with a screw plug 65 allowing access to be had to the valve.

In order to cause the valve 54 to control the rate of flow of gas through the housing 2, utilization is made of the principle governing the flow of fluids whereby if flow is restricted at a point in a fluid conductor, the withdrawal of fluid from one side of the point of restriction will cause the pressure of the fluid on that side to become less than the pressure on the opposite side of the point of restriction. Moreover, when the flow of fluid is thus restricted, the more rapidly it is withdrawn from the conductor, the greater is the pressure differential on opposite sides of the point of restriction. In the illustrated construction, the means for applying the enunciated principle includes a disc 66 inserted in the opening 52 of the wall 50 and being formed in turn with an orifice 68 of relatively small size so as to allow only a restricted flow of gas from the lower portion of the diaphragm chamber 14 to the outlet chamber 46, and thereby cause a drop in pressure in the outlet chamber 46 as gas is withdrawn from the housing through the outlet opening 6. A diaphragm 70, clamped, preferably, between the upper portion of the housing 2 and a ring 72, also constituting part of the housing, is subjected on its under side to the pressure of the gas on the supply side of the orifice disc 66, and a conduit 74 leading from the outlet chamber 46 communicates with the interior of the ring 72 above the diaphragm 70 so as to transmit the pressure of the gas in the outlet chamber 46 to the upper side of the diaphragm. The floor of the outlet chamber 46 is formed with an opening normally closed by a plug 75. Upon removal of the plug 75, this opening allows an orifice disk to be removed and another having a larger or smaller opening to be substituted.

Superimposed on the diaphragm 70 is a plate 76, and disposed beneath the central portion of the diaphragm is a smaller plate 78. An eye 80 is set centrally in the diaphragm 70 and plates 76 and 78 and is flared outwardly at its ends to secure said parts together. The valve stem 58 extends upwardly from the valve 54 and passes loosely through the eye 80, being provided above

the eye with an enlarged portion 82 of larger diameter than the opening in the eye. The weight of the plates 76 and 78, valve 54, and valve stem 58 maintains the diaphragm 70 normally depressed, thus allowing the valve 54 to occupy its fully opened position. When, however, the fluid pressure on the under side of the diaphragm is sufficiently in excess of that on the upper side of the diaphragm to counterbalance the weight of the plates 76 and 78, valve 54, and valve stem 58, the valve tends to close.

Passage of gas through the orifice 68 of the disc 66 induces suction in the space directly above and surrounding the orifice. This suction has a tendency to draw down or "dimple" the portion of the diaphragm 70 above the orifice, and thus to interfere with the proper operation of the valve 54 by the diaphragm. In order to prevent the correct action of the valve from being interfered with in this manner, the plate 76 is extended outwardly beyond the vertical plane of the orifice 68, thus reinforcing the diaphragm above the orifice.

To the end that the valve 54 may be operated also to control the pressure at which gas is delivered from the housing 2, a second diaphragm 84 is provided in the housing above the diaphragm 70. As shown, the periphery of the diaphragm 84 overrides the ring 72 and is clamped thereto by a ring 86 attached to the ring 72 by screws or the like 88. A pendant plate 90 and superimposed plates 92 load the diaphragm 84. The valve stem 58 is provided at its top with a head 94 adapted to be received in a cavity or chamber 95 in the plate 90 of greater cross-sectional dimensions than the head. The plate 90 is formed with a portion underlying the head 94 and provided with an opening of greater diameter than the enlarged portion 82 of the valve stem 58 to allow the valve stem to be raised independently of the plate 90 or diaphragm 84. With this construction, however, when the diaphragm 84 is raised, the valve 54 will also be raised. A plug 96 closes the chamber 95 to prevent the passage of gas about the valve stem 58 to the space above the diaphragm 84 and co-operates with screws 97 in attaching together the plates 90 and 92 and the diaphragm 84. The top of the housing is preferably provided with a cap 98 having openings 99 permitting the upper side of the diaphragm 84 to be subjected to atmospheric pressure. In the illustrated construction, the ring 86 is formed with two substantially semi-circular grooves in which the heads of the screws 88 are received, and which are separated by raised portions 100, to which the cap 98 is secured by screws 101.

Some difficulty was experienced in the commercial development of the illustrated

device by reason of chattering of its movable parts under certain conditions of flow of gas through the device. To the end that this objectionable feature which sometimes attended the operation of the device may be eliminated, the ring 72 is provided with a baffle plate 102 interposed between the diaphragms 70 and 84 and serving to define separate chambers for the diaphragms. The baffle plate 102 is formed centrally with an opening 104 in which the enlarged portion 82 of the valve stem 58 is loosely received. The opening 104 further acts to transmit the pressure of the gas above the diaphragm 70 to the under side of the diaphragm 84. Preferably, and as shown, lugs 106 are cast integrally on the upper side of the baffle plate 102 so as to preclude the weight 90 from moving laterally to an extent sufficient to cause injury to the valve stem 58.

The manner of operation of the illustrated device is as follows:

Assuming that the device is installed in a pipe line of a gas distributing system but that there is no flow of gas through it, the pressure of the gas in the outlet chamber 46 and on the upper side of the diaphragm 70 equals the pressure on the under side of the diaphragm. Consequently, the diaphragm 70 will be fully depressed and, if the diaphragm 84 is also depressed, the valve 54 will occupy its fully opened position. The gas contained in the space defined by the diaphragms 70 and 84 and ring 72, of course, exerts pressure on the under side of the diaphragm 84, as well as on the diaphragm 70. The maximum allowed pressure of the gas in the outlet chamber 46 is determined by the weight of the plates 90 and 92, valve 54 and valve stem 58, it being apparent that when the pressure of gas in the outlet chamber 46 is sufficiently above atmospheric to counterbalance the weight of the above mentioned parts, the valve 54 will tend to close. The tendency of the valve 54 to close under the conditions specified exists whether gas is or is not flowing through the device.

If a relatively small amount of gas is withdrawn from the outlet chamber 46, for example, by reason of the lighting of a few burners in a house piping controlled by the device, the pressure in the outlet chamber 46 will be slightly decreased as compared with that in the lower portion of the diaphragm chamber 14, thus inducing a slight flow of gas through the device. The pressure differential in the chamber 46 and the lower portion of the diaphragm chamber 14 is transmitted to opposite sides of the diaphragm 70. The maximum differential across the diaphragm 70 and, consequently, the maximum rate of flow of gas through the housing 2 is determined by the weight of the plates 76 and 78, valve 54 and valve stem 58 and the size of the orifice 68. So

long as the flow of gas through the housing 2 is below the maximum rate, the diaphragm 70 will not operate to close the valve 54, which, under such conditions of flow of gas is under the control of the diaphragm 84. Inasmuch as the stem 58 of the valve 54 passes loosely through the eye 80 of the diaphragm 70, the valve may be operated by the diaphragm 84 independently of the diaphragm 70.

If the consumption of gas from the piping controlled by the device is increased, for example, by the ignition of burners or stoves, the maximum differential may be set up across the diaphragm 70, thus marking the maximum rate of flow of gas through the device. The rapid withdrawal of gas from the outlet chamber 46 incidental to the establishment of the maximum rate of flow of gas through the device causes the pressure in the outlet chamber 46 and, consequently, on the upper and lower sides of the diaphragms 70 and 84 respectively to be relatively small. As a result, the diaphragm 84 will occupy its lowermost position under the action of the weight of the parts associated with it. The diaphragm 84 operates at all times to prevent the pressure of the gas in the outlet chamber 46 from exceeding a predetermined maximum and further tends, so long as the pressure on the inlet side of the device exceeds the maximum delivery pressure and the rate of flow of gas is below the predetermined maximum, to maintain the pressure in the outlet chamber 46 at the maximum prescribed pressure, inasmuch as the diaphragm 84 will be depressed in the event that the pressure of the gas in the outlet chamber 46 falls below the prescribed maximum, thus opening the valve 54 more widely and enabling a larger flow of gas through the device.

From the foregoing, it will be understood that when the flow of gas through the device tends to exceed the maximum rate determined by the weight of the plates 76 and 78, valve 54 and valve stem 58 and the size of the orifice 68, the upper diaphragm 84 is no longer operative to control the valve 50, the action of the valve being then governed entirely by the diaphragm 70. In the event of movement of the valve 54, in preserving a uniform flow of gas, the enlargement 94 of the valve stem 58 moves upwardly and downwardly in the cavity 95 in the plate 90. If, after the maximum rate of flow has been established through the device, the piping controlled by it is further opened, as for example, by the lighting of additional burners or stoves, the pressure in the outlet chamber 46 is decreased, at the same time inducing a lower pressure in the lower portion of the diaphragm chamber 14. However, if at any time the pressure differential on opposite sides of the diaphragm

70 increases beyond that for which the device is constructed, the valve 54 will tend to close. Consequently, if an attempt is made to take from a line of piping controlled by the device, an amount of gas in excess of the demand limit set by it, the result will be to reduce the gas pressure in the line without increasing the rate of flow. Whenever the rate of flow of gas after having attained 10 the maximum degree is reduced below such degree, the valve 54 again comes under the control of the pressure regulating diaphragm 84.

In passing through meters, such, for example, as those employed to measure domestic consumption, gas undergoes a considerable drop in pressure. In the use of devices containing valves for controlling the flow of fluid and having a valve actuating element or elements located directly in the path of flow of the fluid, it is found, in the event that the fluid is introduced into the device at high pressure, that the valve may be prevented from functioning properly by 20 the velocity with which the gas acts on the valve actuating element. An important advantage of the illustrated device is that the diaphragms are so disposed as not to be affected appreciably by any influence other than differences in the static pressure of the gas. Consequently, the device will operate satisfactorily either on the inlet or outlet side of a meter.

The maximum allowed rate of flow of gas 35 through the device may be increased by adding to the weight of the load on the diaphragm 70 or by employing a disc 66 having a larger orifice than the disc previously in use. Likewise, the pressure at which gas is delivered from the device may be increased or decreased by increasing or decreasing the load on the diaphragm 84.

In cases where the mains are large enough to deliver an adequate supply of gas even 45 though the pressure in them is relatively low, it may not be necessary or advisable to regulate the pressure in the service lines. Under such conditions, the device of this invention may be utilized to limit the demand on the lines without pressure regulation. To this end, the ring 72 and the parts carried by it, including the diaphragm 84 and cap 98, may be removed and a solid cap 108 substituted therefor, as indicated in Fig. 10. 55 The cap 108 is provided with a duct 174 analogous to the duct 74 in the ring 72. In this form of the device, the valve stem 58 is fitted tightly into the eye 80 of the diaphragm 70 so as to cause the valve 54 to partake of all of the movements of the diaphragm. The construction and operation 60 of the diaphragm 70 and valve 54 in the latter form of the device do not, it is believed, require further explanation, inasmuch as they are similar to that of corresponding

parts in the device when constructed to serve both as a demand limiting and pressure regulating device.

The invention having been thus described, what is claimed as new and is desired to be 70 secured by Letters Patent of the United States is:

1. In a fluid controlling mechanism, a fluid conductor, means for causing a drop in pressure of fluid passing through the conductor, a valve for controlling the flow of fluid through the conductor, means for operating the valve in accordance with the pressure differential of the fluid on opposite sides of the first-mentioned means to limit the rate 75 of flow of fluid through the conductor, and means for regulating the pressure at which fluid is delivered from the conductor.

2. A fluid controlling mechanism wherein a difference of pressure therein influences 80 devices controlling the pressure at which the fluid is delivered therefrom when delivering a variable volume of fluid and in which a pressure differential in fluid passing there- 85 through influences devices controlling the volume of flow of fluid when delivering fluid under variable pressure.

3. A fluid controlling mechanism having 90 devices for causing a drop in pressure of fluid passing through a conductor therein 95 and devices adapted to utilize the pressure differential on opposite sides of said first-mentioned devices to control the flow of fluid through the conductor and other de- 100 vices for regulating the pressure at which the fluid is delivered from the conductor.

4. In a combined demand limiting and 105 pressure regulating mechanism for use in gas distributing systems, a conductor for gas, means for causing a drop in pressure of gas 110 passing through the conductor, a valve for controlling the flow of gas through the conductor, a diaphragm for operating the valve in accordance with the pressure differential of the gas on opposite sides of said means, and a second diaphragm operatively connected to the valve and arranged to be controlled by the pressure of the gas on the delivery side of the conductor.

5. In a combined demand limiting and 115 pressure regulating device for use in gas distributing systems, a conductor for gas, a valve for controlling the flow of gas through the conductor, and a plurality of diaphragms 120 joined to the valve by lost motion connections, said conductor and lost motion connections being constructed and arranged to cause the valve to be controlled in its position by one of the diaphragms under cer- 125 tain conditions of flow of gas through the conductor, and to cause the valve to be controlled in its position by another of the dia- phragms under certain other conditions of flow of gas through the conductor.

6. In a fluid controlling mechanism, a 130

- fluid conductor, means for controlling the flow of fluid through the conductor comprising a valve arranged to approach its closed position when it is raised, a pair of loaded diaphragms, connections between the diaphragms and the valve constructed to raise the valve upon elevation of either of the diaphragms, and means for causing each of the diaphragms to be raised under certain different conditions of flow of fluid through the conductor.
7. In a fluid controlling device, a valve, a pair of diaphragms, mechanism for providing a point of restricted flow of fluid in its passage through the device to induce a drop in pressure of the fluid, a housing for the valve, diaphragms and mechanism, constructed to cause the pressure of the fluid on the supply side of the point of restricted flow to be transmitted to one side of one of the diaphragms, to cause the pressure of the fluid on the delivery side of the point of restricted flow to be transmitted to the other side of the first-mentioned diaphragm and against one side of the other diaphragm, and to cause the other side of the second-mentioned diaphragm to be subject to atmospheric pressure only, and connections between the diaphragms and the valve constructed to cause the valve to approach closed position upon movement of either of the diaphragms by pressure of the fluid.
8. In a fluid controlling device, a valve arranged to approach its closed position when it is raised, a pair of superposed diaphragms, mechanism for providing a point of restricted flow of fluid in its passage through the device to induce a drop in pressure of the fluid, a housing for the valve, diaphragms and mechanism, constructed to cause the pressure of the fluid on the supply side of the point of restricted flow to be transmitted to the under side of one of the diaphragms, to cause the pressure of the fluid on the delivery side of the point of restricted flow to be transmitted to the upper side of the first-mentioned diaphragm and against the under side of the other diaphragm, and to cause the upper side of the second mentioned diaphragm to be subject to atmospheric pressure only, and connections between the diaphragms and the valve for causing the valve to be raised upon elevation of either of the diaphragms.
9. In a fluid controlling device, a housing constructed to allow fluid to pass through it and fluid-controlled means in the housing for limiting the rate of flow of fluid through the housing to a predetermined maximum amount and regulating the pressure at which fluid is delivered from the housing.
10. In a fluid controlling mechanism, a fluid conductor, an orifice disk for causing a drop in pressure of fluid passing through the conductor, means governed by the pressure differential on opposite sides of the disk for controlling the flow of fluid through the conductor, and means for limiting the pressure at which fluid is delivered from the conductor.
11. In a fluid controlling mechanism, a fluid conductor, means for maintaining the fluid on the delivery side of the conductor at a predetermined pressure of lesser degree than the pressure of the fluid on the supply side of the conductor, and means for rendering the first-mentioned means inoperative to maintain the fluid on the outlet side of the conductor at such predetermined pressure when the flow of fluid through the conductor exceeds a predetermined rate.
12. In a fluid controlling mechanism, a fluid conductor, a valve for controlling the flow of fluid through the conductor, means for operating the valve to maintain the fluid on the delivery side of the conductor at a predetermined pressure of lesser degree than the pressure on the supply side of the conductor, and means operable on the valve to cause it to limit the flow of fluid through the conductor to a predetermined rate and acting to render the first-mentioned means inoperative on the valve when the flow of fluid attains such rate.
13. In a combined demand limiting and pressure regulating device for gas distributing systems, a conductor or gas, a valve for controlling the passage of gas through the conductor, a diaphragm for operating the valve to cause gas to be delivered from the conductor at a predetermined pressure, and a second diaphragm operable to allow the valve to be controlled by the first-mentioned diaphragm only so long as the flow of gas is below a predetermined rate and to limit the flow of gas to such predetermined rate.
14. In a fluid controlling device, a fluid conductor, a valve for controlling the passage of fluid through the conductor, and a pair of diaphragms operable to control the valve selectively and independently in accordance with varying conditions of flow of fluid through the conductor.
15. In a fluid controlling device, the combination with a housing constructed to provide an inlet chamber, a diaphragm chamber, passages extending downwardly from the diaphragm chamber, ports establishing fluid communication between the inlet chamber and the diaphragm chamber and passages respectively, an outlet chamber, and a duct leading from the outlet chamber to the diaphragm chamber, of a double valve for controlling the flow of fluid through the ports, a diaphragm operatively connected to the valve and located in the diaphragm chamber below the point of communication of the duct with the diaphragm chamber, and an orifice disk disposed in the housing.

between the diaphragm chamber and the outlet chamber for causing a drop in pressure of fluid passing through the device, the arrangement being such that the pressure of the fluid on the supply side of the orifice disk is transmitted to the under surface of the diaphragm and the pressure of the fluid in the outlet chamber is transmitted to the upper side of the diaphragm so as to cause the valve to be controlled in its position by the differential pressures on opposite sides of the orifice disk.

16. In a fluid controlling mechanism, a housing formed to provide a diaphragm chamber and an outlet conduit separated by a substantially horizontal wall, an orifice disk disposed in said wall for causing a drop in pressure of fluid passing from the diaphragm chamber to the outlet conduit, a valve for controlling the flow of fluid through the housing, means for operating the valve comprising a diaphragm disposed above and in substantial parallelism with the orifice disk, a loading plate for the diaphragm extending peripherally beyond the orifice in the orifice disk so as to prevent the portion of the diaphragm above the orifice disk from being drawn downwardly by suction arising from the flow of fluid through the orifice of the disk, and means for transmitting the pressure of the fluid in the outlet conduit to the upper side of the diaphragm so as to cause the valve to be operated in accordance with the pressure differential on opposite sides of the orifice disk.

17. In a fluid controlling mechanism, the combination with a housing constructed to provide an inlet chamber, a diaphragm chamber, and passages extending downwardly from the diaphragm chamber, of a valve cage removably seated in the housing and provided with ports for establishing fluid communication between the inlet chamber and the diaphragm chamber and passages respectively, a double valve for controlling the flow of fluid through the ports from the inlet chamber to the diaphragm chamber and the passages, a diaphragm in the diaphragm chamber operatively connected to the valve, and means for causing a drop in pressure of fluid passing through the housing, said housing being constructed to transmit the pressure differential on opposite sides of said means to opposite sides of the diaphragm to cause the valve to be controlled in accordance with such pressure differential.

18. In a fluid controlling device, a valve, a pair of superposed diaphragms disposed above the valve, an eye on the lower diaphragm, a stem on the valve constructed to pass loosely through the eye and provided above the eye with an enlarged portion incapable of passing through the eye, a part connected to the other diaphragm and con-

structed loosely to receive the upper end of the valve stem, a second enlargement on the valve stem adapted to interlock with said part upon upward movement of the diaphragm and the part, and a housing for the valve and the diaphragms constructed to induce movements of the diaphragms in accordance with varying conditions of flow of fluid through the device.

19. In a fluid controlling mechanism, a valve, a pair of superposed diaphragms disposed above the valve, an eye on the lower diaphragm, a stem on the valve constructed to pass loosely through the eye and provided above the eye with an enlarged portion incapable of passing through the eye, a part connected to the other diaphragm and constructed loosely to receive the upper end of the valve stem, a second enlargement on the valve stem adapted to interlock with said part upon upward movement of the diaphragm and the part, means for causing a drop in pressure of fluid passing thru the mechanism, and a housing for the valve, diaphragms, and said means constructed to induce movement of the lower diaphragm in accordance with the pressure differential on opposite sides of the said means and to induce movement of the upper diaphragm in accordance with the pressure at which fluid is delivered from the mechanism.

20. In a fluid controlling device, a housing constructed to allow fluid to pass through it, a valve for controlling the passage of fluid through the housing, a diaphragm in the housing, a valve stem for connecting the valve with the diaphragm, a plate for loading the diaphragm, and lugs on the housing arranged to limit the lateral movements of the plate so as to prevent injury to the valve stem.

21. In a fluid controlling device, a housing constructed to allow fluid to pass through it, a valve for controlling the passage of fluid through the housing, a stem extending upwardly from the valve and provided with a diametrical enlargement on its upper end, a diaphragm in the housing, a plate secured to the under side of the diaphragm and constructed to provide a chamber of larger cross-sectional dimensions than the enlargement on the valve stem to receive such enlargement and a portion adapted to underlie the enlargement so as to allow lost motion between the diaphragm and the valve and to cause the valve to be raised upon elevation of the diaphragm, and means for closing the upper end of the chamber to prevent passage of fluid from beneath the diaphragm to the upper side of the diaphragm.

22. In a fluid controlling device, a housing constructed to allow fluid to pass through it, a valve for controlling the passage of fluid through the housing, a stem on the valve

having an enlargement on its upper end, a diaphragm in the housing, a plate on the under side of the diaphragm constructed to provide a chamber of larger cross-sectional dimensions than the enlargement on the 5 valve stem to receive such enlargement and a portion adapted to underlie the enlargement on the valve stem so as to allow lost motion between the diaphragm and the valve 10 and to cause the valve to be raised upon upward movement of the diaphragm, and a screw plug for securing the plate to the diaphragm and closing the upper end of the chamber so as to prevent the passage of 15 fluid from beneath the diaphragm to the upper side of the diaphragm.

23. In a fluid controlling mechanism, a fluid conductor, means for causing a drop in pressure of fluid passing through the conductor, 20 a valve for controlling the passage of fluid through the conductor, a diaphragm for operating the valve in accordance with the pressure differential of the fluid on opposite sides of said means, a second diaphragm 25 operatively connected to the valve and arranged to be controlled by the pressure of the fluid on the delivery side of the conductor, chambers for the diaphragms, and means for establishing fluid communication between the top of one of said chambers and 30 the bottom of the other chamber.

24. In a fluid controlling mechanism, a fluid conductor, a valve controlling the passage of fluid through the conductor, a diaphragm 35 connected to the valve, a housing for the diaphragm, a baffle in the housing positioned to divide the housing space into an entrance chamber and a diaphragm chamber, each of said chambers having a comparatively 40 large volume, said housing being connected with the outlet side of the conductor in such a manner that the only entrance of fluid from the outlet side of the conductor is into the entrance chamber, and a restricted opening in the baffle constituting 45 the sole passage of fluid from the entrance chamber to the diaphragm chamber.

25. In a fluid controlling device, a housing constructed to permit fluid to pass through 50 it, a valve for controlling the passage of fluid through the housing, a plurality of

superposed diaphragms in the housing, lost motion connections between the diaphragms and the valve, said lost motion connections and the housing being constructed to cause the valve to be controlled by one of the diaphragms under certain conditions of flow of fluid through the housing and to cause the valve to be controlled by the other diaphragm under certain other conditions of flow of fluid through the housing, and a baffle plate interposed between the diaphragms.

26. In a fluid controlling device, a valve arranged to approach its closed position when it is raised, a pair of superposed diaphragms, mechanism for providing a point of restricted flow of fluid in its passage through the device to induce a drop in pressure of the fluid, a housing for the valve, 65 diaphragms and mechanism, constructed to cause the pressure of the fluid on the supply side of the point of restricted flow to be transmitted to the under side of one of the diaphragms, to cause the pressure of the 70 fluid on the delivery side of the point of restricted flow to be transmitted to the upper side of the first-mentioned diaphragm and against the under side of the other diaphragm, and to cause the other side of the 75 second-mentioned diaphragm to be subject to atmospheric pressure only, connections between the diaphragms and the valve for causing the valve to be raised upon elevation of either of the diaphragms, and a baffle 80 plate interposed between the diaphragms.

27. The combination of a gas conduit, valve means governing the flow of gas through said conduit, a pair of diaphragms controlling said means and having operating connections therewith and one of said diaphragms having one side exposed to the atmosphere and the other exposed to the pressure of gas from said conduit, and means in the path of the gas passing through said 90 conduit for producing a drop in pressure in said gas, the other of said diaphragms being exposed on one side to the pressure of said 95 gas after passing through said means.

In testimony whereof I affix my signature.

JAMES POWELL FISHER.
